UNITED STATES PATENT OFFICE.

ALBERT AICHELE, OF BADEN, SWITZERLAND, ASSIGNOR TO AKTIENGESELLSCHAFT
BROWN, BOVERI & CIE, OF BADEN, SWITZERLAND.

INSULATING-SLEEVE.

1,296,731.

Specification of Letters Patent. Patented Mar. 11, 1919.

Application filed October 4, 1916. Serial No. 123,982.

To all whom it may concern:

Be it known that I, ALBERT AICHELE, a citizen of the Swiss Republic, residing at No. 10 Wiesenstrasse, Baden, Switzerland, have invented certain new and useful Improvements in Insulating-Sleeves, of which the following is a specification.

Insulating sleeves constructed as bodies of revolution with a concave contour, have been found very satisfactory in use for the purpose of preventing discharge over or around the ends and along the surface of such sleeves. In the manufacture of such sleeves of porcelain for instance, the concave contour was conveniently made with a smooth surface. In the manufacture of such insulator sleeves of other materials, however, great difficulties have in some cases been experienced in forming the smooth concave surface.

For instance, in making the insulator by coiling paper that has been impregnated with synthetic resin ("bakelite") or other substances, it has been necessary for producing the smooth concave surface, to arrange that the width of the paper strip to be coiled shall taper in an exactly determined and continuous manner. Since, however, very great lengths of strip have to be coiled, the requisite preliminary shaping of the paper obviously presents very considerable difficulties.

If the width of the paper is tapered in coarse stages, the coiling produces a plurality of cylinders of different lengths coiled on one another, and these cylinders could be turned down to the desired concave contour. That method however, is accompanied with difficulties because the impregnated paper which is coiled hot, becomes extremely hard on cooling and is difficult to machine, while there is considerable waste.

It has also already been proposed, instead of forming the insulator sleeves by coiling, to form them by pressing in a mold an insulating material composed for instance, of fiber and synthetic resin. That method, while allowing of the formation of a smooth concave surface, is limited to small insulators (insulators for low voltages) owing to the expense of large molds, and the difficulty of heating these uniformly.

In the case of large insulators the long inner portion might be formed by coiling

around the central tube, and the thicker and shorter outer portion might be molded around the said inner portion so that only a small mold would be necessary. The formation of a smooth concave surface will however, require a turning of the junction of the coiled and the molded portions, which turning operation presents the above stated difficulties.

The present inventor has now discovered that it is not necessary that the concave surface shall be smooth, but that it may be stepped and still be efficient.

The present invention now has for its object to provide an improved insulating sleeve of the type hereinbefore specified.

According to this invention the insulating sleeves are made partly of layered material and with a stepped concave surface.

An embodiment of this invention is illustrated in the accompanying drawings in which:

Figure 1 is a central longitudinal section of an improved insulating sleeve composed wholly of layered material.

Figs. 2 and 3 are similar views of two modifications composed partly of layered and partly of molded material.

Referring to Fig. 1, the improved insulating sleeve is composed of cylinders a' to a^e of different lengths, graduated in such a manner that the stepped surface of the concave contour of the insulator approximates to the smooth contour represented by the dot and dash line shown in the figure. d is the conductor, and f is the socket or holder for the insulating sleeve.

According to the modification shown in Fig. 2, the insulating sleeve is composed of a tubular member consisting of one or more coiled tubes a and a molded member consisting of a mass of insulating material b pressed or molded around the tubular member a . The concave contour is formed with one or more steps. In using a molded insulating member, advantage may be taken to make the bulge of the said member overlap as shown, the socket or support f , as is usual in the case of porcelain insulating sleeves.

The modification shown in Fig. 3 illustrates an insulating sleeve of great width and small length such as is used for carrying a conductor through a wall.

In this example the insulating sleeve comprises a cylinder *a* layered around the conductor *d*, a plate of layered insulating material which is supported by the wall *f*, and a molded member *b* which serves to connect and hold together the parts *a* and *c*. The member *b* is formed with the concave contour which is continued in the stepped manner hereinbefore described.

Having now described my invention, what I claim as new and desire to secure by Letters Patent is:—

1. In an insulating sleeve the combination of a tubular member composed wholly of graduated layered insulating material and an outer member composed wholly of molded insulating material, having a smooth concave contour, the joint external surface

of the two members constituting a stepped contour of a concave form.

2. In an insulating sleeve the combination of a tubular member composed of layered insulating material around a conductor and a member composed of molded insulating material, having a smooth concave contour with a plate-shaped member of layered insulating material located between said molded member and supported on an internal projection within the wall of a socket or the like.

In testimony whereof I have signed my name to this specification.

ALBERT AICHELE.
